UNITED STATES PATENT OFFICE.

KOBY KOHN, OF NEW YORK, N. Y., ASSIGNOR TO VICTORY SPARKLER & SPECIALTY CO., OF ELKTON, MARYLAND, A CORPORATION OF DELAWARE.

AMUSEMENT AND PROTECTIVE DEVICE.

Application filed December 27, 1923. Serial No. 683,065.

This invention relates to toys, and more especially to toys of the firework class.

One of the objects of this invention is to provide a holder for sparklers or other light sources with a protective guard arranged between the light source and the person viewing it.

Another of the objects of this invention is to provide a novel and amusing toy for use 10 with sparklers and analogous lights and adapted to show sparks or light of a different color than that emanating from the light source.

Another feature of the invention is to 15 provide a device intended to give unique optical effects when used in connection with various light sources and more particularly with what are generally known as sparklers.

A further object of the invention is to 20 provide a simple structure by which the sparks and light from a sparkler are made to take on various colors and intermittently change color without having any relative movement or rotation between the sparkler 25 and the color screen.

In order to attain the above objects I have devised a construction including a rod or stick adapted to be held at one end in the hand and at the other end to support a 30 sparkler and having a guard, which may comprise a disk or sheet of fire resistant material arranged between the ends of the rod. An opening is provided in the disk in which is arranged one or more strips of 35 transparent colored material so disposed that they come between the eye of the operator and the ignited portion of a sparkler. The whole is adapted to be moved by the hand in arcs or circles whereby the observer notes 40 simultaneously sparks of each of the colors of the transparent members covering the opening in the disk and, at the same time, sees a series of concentric bands of color, each one corresponding to one of the above 45 mentioned colors. Means is provided whereby at will the operator may observe a single colored ring of light corresponding to any one of the colors arranged in the opening in the disk.

50 The novel features of this invention will be more fully understood from the following description and claims taken in connection with the accompanying drawings.

In the drawings:

55 Figure 1 is a perspective view of the de-

vice showing a sparkler arranged in position and ready to be lighted.

Figure 2 is a longitudinal section through the device, a portion of the stick being shown in elevation.

Figure 3 is a section on line 3—3 of Figure 1 showing the manner of mounting the transparent colored strips on the disk.

Referring to Figure 1, it will be seen that the device includes a small cylindrical rod 65 or stick 1, preferably formed of hard wood, and having at one end a longitudinal saw cut 2 of suitable width so that the sides thereof may snugly engage the wire or stem 3 of any well-known type of sparkler 4, the natural resilience of the wood serving to adapt the device to various size sparklers. Preferably this end of the rod is treated with a fire proofing solution. Arranged between the ends of the rod 1 and rigidly fastened thereto is a tapered sleeve 5 having at one end thereof a radial flange 6.

An opaque disk 7 formed of any suitable material, but preferably cardboard which may be fire proofed if desired, is provided 80 with a hole 8 snugly fitting over the tapered sleeve 5 so that the disk abuts the flange 6, thus being supported rigidly but adjustably in relation to the rod 1 and at right angles thereto.

The disk 7 is preferably of circular or elliptical shape with the hole 8 close to one edge thereof and is so positioned in relation to the rod 1 that its largest area is directly between the observer who grasps one end of the rod, and the combustible portion of the sparkler 4. An aperture 9 of generally 90 rectangular shape is arranged in the disk 7 in such a position and of such length that an observer grasping the rod 1 and holding the device with the arm extended may observe the full length of the combustible portion of a sparkler through this opening.

Strips 10 and 11 of any suitable transparent medium, such as gelatine, are fastened 100 longitudinally across the opening 9 such as by a suitable adhesive holding their ends against the surface of the cardboard. I have shown four of these strips and they are of alternate colors, such as red and blue, but it is to be understood that any desired number and color of strips may be used. The red strips 10 and blue strips 11 are spaced apart leaving the small slots 12 clear, and since 105 gelatine is a very fragile material it may be 110

desirable to cover these strips with one large sheet of somewhat thicker transparent gelatine 13, which is securely fastened to the cardboard by all of its edges and thus tends 5 to maintain the more fragile strips 10 and 11 in position and protects them from mechanical injury. It will be seen from the above description that the opening 9 in the disk 7 is covered by a screen comprised of vertical 10 strips of transparent material arranged in the order red, white and blue and occurring twice. The larger gelatine sheet 13 is preferably uncolored, or may be milk white.

To operate the device, the end of the rod 15 remote from the sparkler is firmly grasped, the sparkler lighted, the arm extended, and the hand then rotated in any desired arc or circle keeping the colored strips on the disk in a vertical position. The operator will 20 then observe the sparkler and the sparks emanating therefrom through the colored strips successively, and the sparks will appear in the example described above as red, white and blue, and if the sparkler is in a 25 direct line from the eye and the middle open space 12, a ring of light will be observed of the diameter in which the device is rotated. This ring of light is composed of alternating red, white and blue segments in 30 the order named.

The opening 8 in the disk 7 is a snug fit on the sleeve 5, but may be adjustably rotated thereon, and when this is done in such a direction that the blue colored gelatine comes 35 between the observer's eye and the sparkler, a blue circle of light will be seen emanating from the point of combustion of the sparkler, and by turning the disk in the opposite direction a corresponding red circle of light 40 will be observed, it being understood of course that red, white and blue sparks are seen at the same time irrespective of the position of the disk 7 upon the sleeve 5.

An alternative method of operating my device is as follows:

Hold the rod 1 lightly in the hand and after igniting the sparkler rotate the hand allowing the rod to slip therein, so that disk 50 7 and sparkler 4 rotate therewith. This will cause a large ring of red, white and blue sparks to be seen, the diameter of the ring being approximately twice the distance from the rod to the outer edge of the opening 9 in the disk 7. Concentric red, white and 55 blue rings of light will also be seen as described above.

It may be found desirable instead of using independently colored strips of gelatine or other transparent material to use one sheet 60 of such material with the various colored strips painted, printed or dyed thereon. This construction is probably preferable since it is stronger mechanically and offers greater ease of assembly and thus cheapens 65 the manufacturing cost of the final product.

Although I have mentioned the use of gelatine as being preferable for the colored strips in this invention, any desired colored transparent or translucent material may be used, such as glass, colored paper, colored mica, etc., and any desired colors may be used, red, white and blue being merely mentioned in this description as an example, since it is quite customary for sparklers to be extensively used on the fourth of July, and for 70 other patriotic celebrations.

It is well known that the sparks from the average sparkler are usually harmless, but the combustible material of the sparkler at the point of burning has a very high temperature and sometimes drops of molten material fall from the sparkler. Small children are often trusted with sparklers under the misapprehension that they are entirely safe, and a number of painful and a few serious accidents have resulted from children being burned by sparklers. My device 80 effectively prevents such accidents since there is arranged between the operator and the sparkler a disk of fire resistant material, while at the same time, the rod 1 is of such length as to hold the sparkler a material distance from all portions of the operator, and hence the danger of being burned is considerably 85 lessened if not entirely removed.

While I have described the above device in but one form, it will be obvious to those skilled in the art that it may be constructed in various manners, and I do not desire to be limited to the modification shown, except 90 as set forth in the following claims.

Having thus described my invention what I claim and desire to secure by United States Letters Patent is:

1. In a color changer for sparklers and the like, a holder for a sparkler adapted to be grasped in the hand, and a transparent colored medium rigidly mounted between the sparkler and the portion of the holder 105 adapted to be grasped.

2. In a color changer for sparklers and the like, a rod adapted to be grasped at one end, means for supporting a sparkler at the other end thereof, and a multi-colored screen fixed intermediate said ends.

3. In a device for viewing sparklers and the like, means for supporting a sparkler, a handle, and a stationary transparent screen between said handle and said supporting means.

4. In a device for viewing sparklers and the like, means for supporting a sparkler, a handle, and a protective screen non-rotatively mounted between said handle and said supporting means.

5. In a device for viewing sparklers and the like, a rod, means at one end thereof for supporting a sparkler, an opaque disk mounted on said rod between the ends thereof, an opening in said disk opposite the

combustible portion of said sparkler, and a transparent multicolored medium in said opening.

6. In a device for viewing sparklers and the like, a rod slotted at one end and adapted to engage the uncoated portion of a sparkler to support the same, and a transparent particolored screen mounted on said rod.

10 7. In a device for viewing sparklers and the like, a rod slotted at one end to support a sparkler, an opaque disk mounted in a plane at right angles to said rod and rigidly fixed thereto, an aperture in said 15 disk opposite the combustible portion of said sparkler and parallel strips of differently colored transparent media covering said aperture.

8. In a toy device, a sparkler, a rod having a clamp at one end thereof to rigidly hold the sparkler thereon, an opaque disk eccentrically mounted on said rod and having an opening covered by a particolored transparent screen, and means whereby the 25 rod may be moved in circles while viewing the sparkler through the screen.

9. In a toy and protective device for viewing sparklers, a rod having one end adapted to be held by the operator, means on the opposite end of said rod for supporting a sparkler, and a spark resistant shield rigidly fastened to said rod and having an aperture covered by a transparent colored medium.

35 10. In a device for viewing sparklers and analogous lights, a rod having means at one end thereof for supporting a sparkler at

right angles thereto, an opaque disk fixed on said rod parallel to said sparkler, an opening in said disk, and two spaced, differently colored strips of transparent medium arranged in said opening parallel to said sparkler. 40

11. In a device for viewing sparklers and analogous lights, a rod having means at 45 one end thereof for supporting a sparkler at right angles thereto, an opaque disk fixed on said rod parallel to said sparkler, an opening in said disk, two spaced, differently colored strips of transparent medium arranged in said opening parallel to said sparkler, and means whereby said strips can be moved slightly out of parallel with said sparkler. 50

12. In a device for viewing sparklers and the like, a rod, means to support a sparkler at one end thereof and an apertured disc intermediate the ends of said rod. 55

13. A device for viewing sparklers and analogous lights including an opaque disk, 60 an aperture in said disk, spaced colored strips of transparent medium arranged in said aperture, and a single transparent sheet covering said opening and protecting said strips. 65

14. In a device for viewing sparklers and the like, in combination, a rod having a slot to grip a sparkler, a handle portion on said rod remote from said slot and an apertured disc intermediate the slot and handle portion. 70

In testimony whereof I hereunto affix my signature.

KOBY KOHN.
